(57) **CLAIM**

The ornamental design for a height-adjustable trailer, as shown and described.

DESCRIPTION

FIG. 1 is a top-rear-left perspective view of a height-adjustable trailer in a lowered configuration;

FIG. 2 is a top-rear-left perspective view thereof in a raised configuration;

FIG. 3 is a top-front-left perspective view thereof in a lowered configuration;

FIG. 4 is a top-front-left perspective view thereof in a raised configuration;

FIG. 5 is a top plan view thereof;

FIG. 6 is a front elevational view thereof in a raised configuration;

FIG. 7 is a rear elevational view thereof in a raised configuration;

FIG. 8 is a right side elevational view thereof in a lowered configuration;

FIG. 9 is a right side elevational view thereof in a raised configuration;

FIG. 10 is a left side elevational view thereof in a lowered configuration; and,

FIG. 11 is a left side elevational view thereof in a raised configuration.

The broken lines shown in the drawings depict portions of the height-adjustable trailer that form no part of the claimed design.
